VICTOR NIVOIS, OF BROOKLYN, NEW YORK.

CONTAINER.

1,193,592.

Specification of Letters Patent.

Patented Aug. 8, 1916.

Application filed July 30, 1914. Serial No. 854,127.

To all whom it may concern:

Be it known that I, VICTOR Nivois, a citizen of France, residing at Brooklyn, in the county of Kings and State of New York, have invented new and useful Improvements 5 in Containers, of which the following is a specification.

This invention relates to containers, and while the invention is capable of use in 10 many connections, it is described and illustrated hereinafter as applied to a cigarette container or case.

The invention is applicable to any container which is opened from time to time in 15 order to facilitate the removal of articles carried in the container.

The invention pertains more particularly to that class of containers in which the articles such as cigarettes are held therein in 20 such a way that when the container is opened they will be raised or brought into a position so that they can be readily removed. In the present instance, I have 25 illustrated a construction in which the container comprises two hinged members at the hinge connection of which a holder for the cigarettes is connected, and the arrangement is such that when the hinged members are 30 swung apart to open the container, the holder for the cigarettes moves out into the angle between the hinged members so that the cigarettes are displayed in a position where they can be readily removed.

The invention consists in the general combination of parts and simplicity of details 35 hereinafter described, all of which contribute to produce an efficient container.

A preferred embodiment of my invention will be particularly described in the following 40 specification while the broad scope of my invention will be pointed out in the appended claims.

In the drawings: Figure 1 is a perspective illustrating a container embodying my 45 invention. Fig. 2 is a plan showing the hinged portion of the container in open position, certain parts being broken away. Fig. 3 is a longitudinal section through the container taken at the hinge connection and 50 illustrating details of form which the invention may take. Fig. 4 is a cross section through the hinge connection on the line 4—4 of Fig. 3, illustrating the parts of the container in their open relation. Fig. 5 is 55 a view somewhat similar to Fig. 2 showing the hinge portion of the container with the

container in its opened position; this view shows a special form of holder for the cigarettes. Fig. 6 is a view similar to Fig. 3 but showing another form the invention may 60 take as to the means of attaching the holder to the hinge connection. Fig. 7 is a cross section about on the line 7—7 of Fig. 6.

Referring more particularly to the parts, the container illustrated may be adapted for 65 carrying any article such as cigarettes or cigars, and this container preferably comprises two members 10 and 11 which, in the present instance, constitute respectively the body and lid of a simple flat box having a 70 hinge connection as at the edge 12. In forming a hinge connection, I prefer to employ a pintle 13, the body 14 of which forms the axis of rotation of the container members upon each other. This pintle 13 has 75 free lateral extensions 15 which are preferably formed at the ends of the pintle by bending the pintle laterally, and these extensions 15 preferably extend substantially at right angles to the body 14 of the pintle. 80 The ends of the extensions 15 are preferably bent to form shanks 16 substantially parallel with the body 14 of the pintle. The pintle may be attached to the members 10 and 11 in any suitable manner, but I prefer 85 to attach the pintle in place by forming a shallow off-set channel 17 in the flange 18 of the member 10; this channel is preferably formed at about mid-height of the flange 18. The extensions 15 are sufficiently long to project be- 90 yond the upper edge of the flange 18 when the pintle is in the position shown in Fig. 4. The flange 18 beyond the channel 17 is pref- 95 erably off-set in an outward direction to form grooves 19 conforming to the shape of the extensions 13 and also receiving the ends of the body 14 of the pintle. The channel 17 is preferably formed by pressing the metal toward the inner side of the flange and the extensions 15 lie on the inner side 100 of the flange.

The member 11 may, if desired, have a flange 20 of less depth than the flange 18 so that this member constitutes a lid. I prefer to attach this member 11 to the body 14 105 of the pintle by forming an integral sleeve 21 on the flange which grips the body of the pintle frictionally. The shanks 16 facilitate the attachment to the pintle of a holder 22. This holder 22 may be of any desired 110 form. In Fig. 1, I have illustrated it as a simple open box which may be formed of

cardboard or thin metal and adapted to contain a row of cigarettes 23 the inner ends of which abut against the bottom wall 24 of the holder. This holder 22 is preferably 5 narrow so that the upper ends of the cigarettes project in some such manner as that illustrated in Fig. 1. If desired, however, the holder for the cigarettes may have the form illustrated in Figs. 5 to 7. In this 10 case, the holder 25 is formed of light sheet metal and consists of two oppositely disposed plates having waves or corrugations 26 forming sockets 27 to receive the cigarettes. A holder of this form is most conveniently produced from a sheet of metal 15 bent or folded upon itself so as to bring its side edges 28 into parallelism. When the holder is made of metal in this way, I prefer to attach the holder to the pintle in the 20 manner illustrated in Fig. 6, wherein 29 illustrates the pintle. The lateral extensions of the pintle in this case are formed with shanks 30 which project in the same direction and the bottom 31 of the holder is 25 preferably punched and off-set so as to form sockets to receive the shanks 30. These sockets are preferably formed by producing an upward off-set 32 and punching downwardly from this off-set an integral tongue 33 so that the shanks 30 are adapted to be 30 shoved into the space between the off-set metal 32 and the tongues 33. At the edge of the off-set portions shoulders 34 are formed and these shoulders perform the 35 function of preventing the withdrawal of the shanks after they have been shoved into position by a longitudinal movement of the shanks in the direction in which they point.

In the mode of operation of the invention, the pintle 13 is freely movable and the 40 arrangement is such that when the members 10 and 11 are swung apart, the sleeve 21 will rotate the pintle and swing the holder up from the container and into the angle 45 between the members, and as long as the member 11 is swinging open, the upward swinging movement of the pintle will continue until its swinging movement is limited by the extensions 15 striking the flange 50 18. This would prevent any further movement of the holder 22 and if desired, the members 10 and 11 can then be moved until they come into substantially the same plane. The open container can then be laid upon 55 a support such as a table with the holder 22 projecting substantially vertically. Evidently the cigarettes may be very conveniently reached and removed from the container.

60 Obviously it is not necessary to open the container to its full open position as the cigarettes may be readily removed in a partially open position of the container. Evidently also, either the member 10 or 11 may 65 be considered as a lid member or body mem-

ber. Furthermore, although I have illustrated the holders 22 and 25 as adapted to hold a single row of cigarettes, evidently these holders may be constructed to carry two or more rows of cigarettes or cigars, or 70 other articles if desired.

It is understood that the embodiment of the invention set forth above is only one of the many embodiments or forms the invention may take and I do not wish to be limited in the practice of my invention or in the construction of my claims to the particular embodiment set forth. 75

What I claim is;

1. A container of the class described comprising 80 two hinged members having a pintle at their hinge connection, said pintle having free projecting parts and a holder attached directly to the said projecting parts of the pintle, said holder being adapted to be 85 inclosed by said members when they are brought together.

2. A container of the class described comprising 90 two hinged members having a pintle at their hinge connection, said pintle having free projecting parts and a holder attached directly to the said projecting parts of the pintle, said holder being adapted to be 95 inclosed by said members when they are brought together, said pintle being freely movable with respect to one of said members in one direction and means for limiting the movement of the pintle with respect to that member in the other direction.

3. A container of the class described comprising 100 a body, a lid to close said body, a hinge pintle connecting said lid and said body to enable said lid to swing open, said hinge pintle having extensions at the ends thereof and a holder attached to said extensions and arranged to fold into the interior of the container when the same is closed. 105

4. A container of the class described comprising 110 a body, a lid to close said body, a hinge pintle connecting said lid and said body to enable said lid to swing open, said hinge pintle having extensions at the ends thereof and a holder attached to said extensions and arranged to fold into the interior of the container when the same is closed, said lid having frictional engagement with said pintle to rotate the pintle when the container is opened and thereby move said holder out into the angle between 115 said body and said lid.

5. A container of the class described comprising 120 two hinged members having a pintle connecting the same, a holder attached to said pintle and lying in the space between said members when the same are brought together, one of said members having a connection with said pintle adapted to rotate said pintle when said members are swung apart, the other of said members having 125 130

means for limiting the movement of said pintle when the holder is projecting into the angle formed between said members.

6. A container of the class described comprising two hinged members, a pintle for hingedly connecting the same, a holder attached to said pintle, one of said members having a flange with a sleeve having frictional engagement with said pintle for rotating the same when said members are swung apart, the other of said members having a flange in the path of movement of the pintle when it is rotated by said sleeve to limit the movement of said pintle and maintain the holder projecting into the angle between said members.

7. A container of the class described comprising two hinged members, a pintle for hingedly connecting the same, said pintle being bent to form laterally projecting extensions, a holder attached to said lateral extensions and adapted to lie between said members when they are brought together, and means for rotating said pintle when said members are moved into substantially the

same plane to maintain said holder projecting in a plane substantially at right angles to the plane of said members.

8. A container of the class described comprising a body having a flange, a pintle rotatably mounted in said flange and having laterally disposed extensions lying on the inner side of said flange which may project beyond the edge of said flange, a holder attached to said extensions and adapted to fold down into said body, and a lid having a sleeve frictionally engaging said pintle and adapted to rotate the same when the lid is opened to swing said holder away from said body and move the same into position with said extensions against said first named flange.

In testimony whereof I have hereunto set my hand in presence of two subscribing witnesses.

VICTOR NIVOIS.
